BI-CONICAL SUPPORT TUBE FOR TEXTILE THREADS

René Sibille, Paris, France, assignor to Papeteries René Sibille, Pont-Eveque, Isere, France, a French body corporate

Filed Oct. 21, 1957, Ser. No. 692,019

Claims priority, application France Apr. 25, 1957
6 Claims. (Cl. 242—118.3)

The present invention relates to bi-conical support tubes for textile threads on which the threads are wound to obtain a twisting of the thread, during this winding. The bi-conical shape of these tubes permits winding thereon great lengths of thread without danger of collapse.

At the present time, solid elements obtained by moulding and notably composed or plastic material are used as bi-conical support tubes. The support tubes thus constructed are heavy and easily broken and their cost price is high. Thus, they can only be used within the factory, which necessitates unwinding the thread from the tube and winding it on an ordinary tube of paper before dispatching the thread to the user.

The object of the invention is to remedy these disadvantages in providing a bi-conical support tube which is lighter and cheaper and can be used as a subsequently discarded packing means sent to the thread user. This permits eliminating the rewinding of the thread before dispatch with the corresponding advantages.

The support tube according to the invention is characterized in that it comprises a cylindrical or conical inner tube and two part-conical members assembled on the inner tube, the cross-sectional shape of the small ends of said members corresponding to the outer cross-sectional shape of the tube whereas their large ends are held centrally of the tube by blocking means.

Advantageously, the blocking means of the conical members are formed by the rolled edges of these members.

Further features and advantages of the invention will be apparent from the ensuing description with reference to the accompanying drawing, to which the invention is in no way limited.

In the drawing:

FIG. 1 a longitudinal axial sectional view of a first embodiment of the invention;

FIG. 2 is a similar view of a modification of the invention, and

FIG. 3 is a similar view of another modification of the invention.

In the embodiment shown in FIG. 1, the bi-conical support tube comprises an inner tube 1 on which are mounted two part-conical members 2^a and 2^b. The inner tube 1 can be cylindrical or slightly tapered as shown in FIG. 1 so as to be adaptable for use on the spindle of a winding machine. The upper edge of the tube 1 could be rolled or formed inwardly as shown at 3 in FIG. 1, so as to constitute means whereby a hold can be obtained on the tube to withdraw it from the winding machine spindle.

The small base 4 of each of the attached part-conical members 2^a and 2^b corresponds in shape to the outer wall of the tube 1. It is held centrally of the tube 1, at its large base 5 by blocking means which is formed, in the presently-described embodiment, by the rolled edge 6 of each member 2^a or 2^b which is fixed to the outer face of the tube 1 by an adhesive.

The two members 2^a, 2^b are in contact with one another at their small base 4 where they may be interconnected by an adhesive.

This arrangement, however, is not essential and FIG. 2 shows another embodiment of the invention which

2

may be used especially for longer support tubes. This second embodiment is identical to that shown in FIG. 1, except that the two part-conical members 2^a and 2^b do not touch one another but are separated by a sleeve 7 the shape of which corresponds to the shape of the tube 1 in its intermediate part. The members 2^a and 2^b abut the ends of the sleeve 7 at their small bases 4. The various members of the support tube may be connected to one another by an adhesive to enhance the rigidity of the unit.

FIG. 3 shows a third embodiment similar to that shown in FIG. 2 except that no sleeve 7 is provided. The small bases of the part-conical members 2^a and 2^b, attached to the inner tube 1 by an adhesive, are tapered or thinned down at 8, for example by a grinding operation, to avoid any step in the region of the joint. The embodiment shown in FIG. 3 is therefore simpler than that shown in FIG. 2 and more easily mass-produced.

The support tube embodying the invention can be made of any suitable material, such as paper, cardboard or plastic material. They have numerous advantages over heavy bi-conical support tubes used heretofore. Their manufacture is simpler and does not require a complicated mould. They are lighter and much cheaper. Thus they can be delivered directly to the customer in the form of subsequently discarded packing means after the winding and twisting of the thread.

Thus, the additional twisting operation at present required in the factory is avoided, this twisting operation consisting in unwinding the thread from the support tube and winding it on a paper tube more suitable for dispatching to the customer.

Thus, a considerable saving in labour and in the workshop space needed for the conventional method is effected. This permits a considerable reduction in the cost price of the twisting operation and increased production.

Although specific embodiments of the invention have been described, many modifications and changes may be made therein without departing from the scope of the invention as defined in the appended claims.

Having described my invention what I claim as new and desire to secure by Letters Patent is:

1. Bi-conical support tube for textile threads, comprising an inner tubular member having an inwardly rolled edge at one of its ends so as to reduce the inner cross-sectional area of said one end into which can thus be fitted the winding spindle of a winding machine, two part-conical members mounted on said inner member with their small ends turned toward one another, the small end of each of said part-conical members having a cross-sectional size substantially identical to the outer cross-sectional size of said inner member and the large end of each of said part-conical members having an inwardly rolled edge so as to reduce the inner cross-sectional area of said large end so that said area is substantially equal to the outer cross-sectional area of said inner member, each of said part-conical members being adhesively secured by means of its rolled edge to said inner member and the rolled edge of one of said part-conical members being adjacent to the rolled edge of said one end of said inner member.

2. Bi-conical support tube as claimed in claim 1, wherein said inner member is conical, said one end having the inwardly rolled edge being the small end.

3. Bi-conical support tube for textile threads, comprising an inner tubular member having an inwardly rolled edge at one of its ends so as to reduce the inner cross-sectional area of said one end into which can thus be fitted the winding spindle of a winding machine, two part-conical members mounted on said inner member with their small ends in abutting relationship, the small end of each of said part-conical members having a cross-

sectional size substantially identical to the outer cross-sectional size of said inner member and the large end of each of said part-conical members having an inwardly rolled edge so as to reduce the inner cross-sectional area of said large end so that said area is substantially equal to the outer cross-sectional area of said inner member, each of said part-conical members being adhesively secured by means of its rolled edge to said inner member and the rolled edge of one of said part-conical members being adjacent to the rolled edge of said one end of said inner member.

4. Bi-conical support tube for textile threads, comprising an inner tubular member having an inwardly rolled edge at one of its ends so as to reduce the inner cross-sectional area of said one end into which can thus be fitted the winding spindle of a winding machine, two part-conical members mounted on said inner member with their small ends turned toward and spaced apart from one another, the small end of each of said part-conical members having a cross-sectional size substantially identical to the outer cross-sectional size of said inner member and the large end of each of said part-conical members having an inwardly rolled edge so as to reduce the inner cross-sectional area of said large end so that said area is substantially equal to the outer cross-sectional area of said inner member, each of said part-conical members being adhesively secured by means of its rolled edge to said inner member and the rolled edge of one of said part-conical members being adjacent to the rolled edge of said one end of said inner member.

5. Bi-conical support tube as claimed in claim 4, wherein said small end of said part-conical members has a chamfered edge by which it is connected and cemented to the outer wall of said inner member.

6. Bi-conical support tube for textile threads, comprising an inner tubular member having an inwardly rolled edge at one of its ends so as to reduce the inner cross-sectional area of said one end into which can thus be fitted the winding spindle of a winding machine, a sleeve mounted without clearance on said inner member and having a length less than the latter so as to provide at each end of the inner member an uncovered part, two part-conical members each of which is mounted on one of said uncovered parts, the small end of each of said part-conical members having a cross-sectional size substantially equal to the cross-sectional size of the outer face of said inner member and being in abutting relationship to one of the ends of said sleeve, and the large end of each of said part-conical members having an inwardly rolled edge so as to reduce the inner cross-sectional area of said large end so that said area is substantially equal to the outer cross-sectional area of said inner member, each of said part-conical members being adhesively secured by means of its rolled edge to said inner member and the rolled edge of one of said part-conical members being adjacent to the rolled edge of said one end of said inner member.
